UNITED STATES PATENT OFFICE.

JOSEPH MITERA, OF PLAINFIELD, NEW JERSEY.

DESIGN FOR A CASING FOR GAS-HEATERS.

59,255.

Specification for Design.

Patented Oct. 4, 1921.

Application filed March 23, 1920. Serial No. 368,103. Term of patent 7 years.

To all whom it may concern:

Be it known that I, JOSEPH MITERA, a citizen of Poland, residing at Plainfield, in the county of Hudson and State of New Jersey, have invented a new, original, and ornamental Design for a Casing for Gas-Heaters, of which the following is a specification, reference being had to the accompanying drawings, forming a part thereof.

The figure is a perspective view of my device.

I claim:

The ornamental design for a casing for gas heaters, as shown.

JOSEPH MITERA.
